UNITED STATES PATENT OFFICE.

JAMES P. MADDEN AND WILLIAM L. LUKENS, OF BETHLEHEM, PENNSYLVANIA,
ASSIGNORS TO BETHLEHEM STEEL COMPANY, OF SOUTH BETHLEHEM, PENNSYLVANIA, A CORPORATION OF PENNSYLVANIA.

DETONATING-FUSE.

1,250,919.

Specification of Letters Patent. Patented Dec. 18, 1917.

Application filed September 6, 1916. Serial No. 118,895.

To all whom it may concern:

Be it known that we, JAMES P. MADDEN, a subject of the King of Great Britain, and residing at Bethlehem, county of Northampton, State of Pennsylvania, and WILLIAM L. LUKENS, a citizen of the United States, and residing at Bethlehem, county of Lehigh, State of Pennsylvania, have invented certain new and useful Improvements in Detonating-Fuses, of which the following is a specification.

This invention relates to percussion fuses, particularly to point percussion fuses, and has for its object to provide a fuse of this class in which the maximum degree of safety in handling is realized. The invention contemplates the use of a plunger to which is attached at one end a firing pin and at the other end a fulminate or other detonating charge, which plunger is "armed" by the spinning of the projectile in which the fuse is secured and which is thrown forward upon impact to bring the firing pin into contact with and to explode a primer and to bring the detonating charge into juxtaposition with a larger boosting charge, the primer firing the detonating charge and the latter detonating the boosting charge, which in turn detonates the bursting charge of the projectile. Centrifugal means controls the arming of the fuse and hence only by firing the projectile from a gun can the fuse be exploded. In this invention the various charges used in the fuse are contained within a casing which can only be ruptured by the explosion of a substantial charge therein designated above as the boosting charge, which is normally apart and insulated from the primer and the detonating charge and can only be detonated when the plunger has been automatically released and has been moved forward, due to the impact of the projectile, and cannot be accidentally detonated by the premature ignition of either the primer or the detonating charge or both. The invention also contemplates a primer which is normally protected from the firing pin and which only becomes exposed thereto by the action of certain parts controlled by the spinning of the shell.

Our invention will be fully disclosed in the following description taken in connection with the accompanying drawings, in which,

Figure 1 is a longitudinal section of the fuse showing parts of a projectile to which it is attached;

Fig. 2 is a section along the line 2—2 of Fig. 1;

Fig. 3 is a section along the line 3—3 of Fig. 2;

Fig. 4 is a section along the line 4—4 of Fig. 1;

Fig. 5 is a section along the line 5—5 of Fig. 1;

Fig. 6 shows a modification of one feature of our invention;

Fig. 7 is a section on line 7—7 of Fig. 6.

In the drawings, 10 indicates the body of a projectile, shown in Fig. 1 in dotted lines, and 11 indicates the body of the fuse which is made detachable from the projectile body and provided with screw threads for its ready attachment thereto. Although we have shown our invention with the body of the fuse conforming to the contour of the projectile, it is obvious that other modes of embodying it may be adopted. The fuse body 11 is recessed at 12 to receive the enlarged end 13 of a cylindrical stock or casing A, suitable screw threads being provided on the exterior of the stock or casing and on the wall of the recess to allow the attachment and detachment thereof. The rearwardly extending portion 14 of the casing A is reduced somewhat in diameter and has a plug 15 screw threaded into the rear end thereof, making the casing gas-tight. Between the forward end of the casing and the forward end of the recess 12 in the body 11 a space is left which is adapted to contain the primer in a manner hereinafter to be more fully explained and which is separated from the main portion of the chamber inclosed within the casing by a brass obturator disk 16 and a screw disk 17, threaded into the end of the casing.

The interior of the casing is divided into three main portions by two partitions, 18 and 19, respectively, the former being integral with the wall of the casing and the latter partition being integral with an auxiliary casing or liner 20, placed in the rear of the casing to strengthen the walls. These partitions are provided with central circular aligned openings 21 and 22, respectively, through which extends a plunger 23. The portion of the plunger extending into the

centrifugal cage cavity (toward the point of the projectile) is enlarged to limit its rearward movement and the rearward portion has a recess 24 therein into which is inserted a fulminate detonator charge 25 contained in a copper tube 26. Felt disk 27 and felt washer 28 are placed at the ends of the copper tube to act as cushions and a threaded plug 29 at the end of the plunger 10 holds the charge, and disks, within the recess 24.

A flame conduit 30 passes axially through the plunger and through the base portion of a plug 31 at the forward end which supports a steel needle or firing pin 32. This plug is screw-threaded into the forward end of the plunger and serves to hold in position black powder delay pellets 33, which are located in an enlarged portion of the flame 20 conduit 30 immediately behind it.

A soft lead shock absorbing pad 50 is placed between the enlarged portion of the plunger and the partition 18 to prevent excessive jar to the fulminate detonating 25 charge on the firing of the projectile.

The firing pin 32 is aligned with an opening 34 in the screw collar 17 and is adapted to be propelled by its inertia through this opening to fire the primer 35, when the projectile's flight is arrested, the plunger having ample energy to drive the pin through the intermediate obturator disk 16.

The primer 35 is mounted in an opening 36 in a centrifugal shutter 37 pivoted on a 35 pin 38 located to one side of the axis of the projectile. A spring 39 pressing upon a projecting portion of the shutter normally maintains it in a central position with the primer at one side and out of the line of 40 action of the firing pin. This is the normal position of the shutter and only when the projectile is spinning rapidly after having been fired from the gun does the shutter move, under the action of centrifugal force, 45 about its pivot 38 to bring the primer into alignment with the firing pin.

Premature explosion of the primer when in its normal position cannot ignite the detonating charge, the expanding gases being received within an expansion chamber 40, in the fuse body and prevented from passing rearwardly in the casing by the obturator disk 16. The primer is held within the shutter by a removable screw threaded 55 plug 41.

In the chamber between the screw disk 17 and the partition 18 is located the centrifugal cage 42, which normally abuts against and prevents the movement of the plunger 60 23. The rapid spinning of the shell throws the segments of the cage outwardly against the wall of the casing, thus disengaging the plunger and "arming" it. When thus disengaged a comparatively light spring 43, 65 which bears against the plunger and collar

17, prevents the plunger from gradually moving forward as the projectile is retarded by the air. This spring, however, is not of such strength as to materially retard the forward movement of the plunger when the 70 projectile strikes its objective.

The intermediate chamber is occupied by a charge 44 called the booster charge, suitably retained within an annular paper or brass casing and insulated from the two 75 partitions 18 and 19 by asbestos washers 45 and 46.

The booster charge is the only charge contained within the fuse which is able to rupture the casing upon exploding and hence 80 the bursting charge of the projectile cannot be detonated unless the booster charge is detonated.

An eccentric ring 47 is contained within a recess 48 in the partition 19 and is loosely 85 mounted upon the plunger as clearly shown in Fig. 5. This ring shifts laterally after the plunger has moved forward upon impact, under the influence of centrifugal force and blocks the return of the plunger to its 90 original position.

To prevent the rear end of the plunger from "whipping" during rotation, a sheet metal support 49 is crimped into the expansion chamber liner 20 and surrounds and 95 supports the plunger.

When the fulminate detonator charge 25 is in its "safe" position, as shown in Fig. 1, a premature explosion is dissipated in the expansion chamber within liner 20, the wall 100 being strong enough to withstand the gas pressure, the asbestos washer 46 and the brass booster charge tube dissipating the heat of the gases so as not to affect the booster charge. 105

When the projectile is fired from a gun and as long as its acceleration continues, the shutter 37 is pressed against the disk which is supported by disk 17 and the primer remains in its unarmed position. As soon as 110 acceleration ceases the shutter is moved by centrifugal force to bring the primer into firing position and at the same time to cut off the flash port into the expansion chamber 40. 115

The centrifugal cage 42 then expands and the plunger is released therefrom, the retaining spring 43 keeping the plunger from the primer. On impact the plunger moves forward, compressing the spring 43 and causing the firing pin or needle to pierce and 120 explode the primer.

The flash ignites the black powder delay pellets 33 and the flash is conveyed then 125 through the flame conduit 30 to the fulminate detonator charge 25, the amount of delay being regulated by the construction of the pellets.

The fulminate detonator charge, owing to the forward travel of the plunger, has been 130

carried into the center of the booster charge, thus detonating the booster charge, which in turn ruptures the fuse casing and detonates the bursting charge of the projectile.

5. By this arrangement the maximum degree of safety is realized for the handlers of the projectiles. If for any reason either the primer or the detonator charge is exploded, as when the projectile is severely jarred, or 10 both the primer and the detonator are exploded, the gases are dissipated in the respective expansion chambers, the booster charge remaining unaffected.

Referring to Figs. 6 and 7, the primer 51 is seated centrally in fuse body 11 and protected by a centrifugal shutter 52, pivoted at 53 and held in normal or protecting position by a spring 54. In all other features the construction shown in Figs. 6 and 7 may 20 be identical with that shown in the preceding figures, and the operation of both forms of the invention is the same excepting that in the first form the primer is moved into alignment with the firing pin on firing, 25 whereas in the second form the primer is always in alignment with the firing pin and is exposed on firing by the shutter.

It is obvious that various modifications may be made in our arrangement of parts 30 and that other ways of forming the gas-tight casing may be employed and hence we do not limit ourselves to the exact form or details shown and described.

Having thus described the invention, what 35 is claimed and desired to be secured by Letters-Patent is,

1. In a percussion fuse for projectiles, a fuse casing, a primer normally spring held in a safe position, centrifugal means actuated by the spinning of the projectile for moving said primer into firing position, a booster charge spaced from said primer, a plunger having therein a flame conduit, a firing pin and a detonator charge secured to 40 the ends of said plunger, automatically released means for normally holding said plunger against movement, said plunger being adapted to be moved upon the impact of the projectile to bring said firing pin into 45 contact with said primer and said detonator charge into juxtaposition with said booster 50 charge.

2. In a percussion fuse for projectiles, a primer, a booster charge spaced therefrom, 55 a plunger passing through said booster charge and having a longitudinal flame conduit therein, a firing pin and a detonator charge secured to the ends of said plunger, automatically released means for normally holding said plunger against movement, said plunger being adapted to be moved upon the 60 impact of the projectile to bring said firing pin into contact with said primer and said detonator charge into juxtaposition with 65 said booster charge.

3. In a percussion fuse for projectiles, a primer, a booster charge spaced therefrom, a plunger passing through the center of said booster charge and having a longitudinal flame conduit therein, a firing pin and a detonator charge secured to the ends of the plunger, the distance between the firing pin and detonating charge being substantially equal to the distance between the primer and the booster charge, automatically released means for normally holding said plunger against movement, said plunger being adapted to be moved upon the impact of the projectile to bring said firing pin into contact with said primer and said detonator 70 charge into juxtaposition with said booster charge, and means inclosing the said elements within a gas-tight casing.

4. In a percussion fuse for projectiles, a primer, a booster charge spaced therefrom, a plunger having therein a flame conduit, said plunger having a recess in the end thereof, a detonating charge secured within the recess, a firing pin and a flash delaying device secured to the other end of the plunger, 85 automatically released means for normally holding said plunger against movement, said plunger being adapted to be moved upon the impact of the projectile to bring said firing pin into contact with said primer and said detonator charge into juxtaposition with said booster charge, and means inclosing the said elements within a gas-tight 90 casing.

5. In a percussion fuse for projectiles, a primer, a booster charge spaced therefrom, a plunger having therein a flame conduit, a firing pin and a detonator charge secured to the ends of said plunger, centrifugally released means comprising an annular member having spring arms with weighted ends for normally holding said plunger against movement, a light spring also tending to hold said plunger against movement, said plunger being adapted to be moved upon 105 the impact of the projectile, against the resistance of said spring, to bring said firing pin into contact with said primer and said detonator charge into juxtaposition with said booster charge, and means inclosing the 110 said elements within a gas-tight casing.

6. In a percussion fuse for projectiles, a primer, a booster charge spaced therefrom and arranged with a longitudinal passage therethrough, a plunger passing through the 120 longitudinal passage in said booster charge, a firing pin and a detonator charge secured to the ends of said plunger, a flash delaying device between said firing pin and detonator charge, automatically released means for normally holding said plunger against movement, said plunger being adapted to be moved upon the impact of the projectile to bring said firing pin into contact with 125 said primer and said detonator charge into 130

the longitudinal passage through said booster charge, and means inclosing said elements within a gas-tight casing.

7. In a percussion fuse for projectiles, a primer, an annular thin walled casing containing a booster charge, a plunger passing through the bore of said annular casing, a firing pin and a detonator charge secured to the ends of said plunger, automatically released means for normally holding said plunger against movement, said plunger being adapted to be moved upon the impact of the projectile to bring said firing pin into contact with said primer and said detonator charge into the bore of said annular booster charge casing, and means inclosing said elements within a gas-tight casing.

8. In a percussion fuse for projectiles, a gas-tight casing having a thick walled expansion chamber at one end and a second chamber adjacent thereto and separated therefrom by a partition having an opening therein, a plunger having a flame conduit therein and a firing pin mounted thereon, said plunger extending through said second mentioned chamber and into said first mentioned chamber, a detonator charge secured to the end of said plunger and normally held within said first mentioned chamber, a primer adapted to ignite said detonator charge, and automatically released means for normally holding said plunger against movement, said plunger being adapted to be moved upon the impact of the projectile to bring said firing pin into contact with said primer and said detonator charge into the chamber containing the booster charge.

9. In a percussion fuse for projectiles, a

gas tight casing having a thick walled expansion chamber at one end, a plunger extending into said chamber, said plunger having a flame conduit and a recess in the end thereof, a detonating charge secured within the recess, a primer, a booster charge spaced therefrom, automatically released means for normally holding the said plunger against movement, a firing pin, said plunger being adapted to be moved upon the impact of the projectile to bring said firing pin into contact with said primer, and said plunger charge into juxtaposition with said booster charge, and means in said explosion chamber bearing against the inner wall thereof, supporting the end of said plunger to steady it during the flight of the shell, said means comprising a light frame not materially decreasing the volume of said expansion chamber.

10. In a percussion fuse for projectiles, a member having a recess therein, said recess being adapted to serve as an expansion chamber for gases, a primer, a plunger having a firing pin adapted to fire said primer upon the impact of the projectile, spring means for normally holding the said primer in a safe position relative to said firing pin and opposite said expansion chamber, automatic means for bringing said primer into firing position and away from said expansion chamber when the projectile is propelled from a gun, and an explosive adapted to be ignited by said primer.

In testimony whereof we affix our signatures.

JAMES P. MADDEN.
WILLIAM L. LUKENS.
